UNITED STATES PATENT OFFICE.

EDWARD POOLE, OF PHILADELPHIA, PENNSYLVANIA.

DESIGN FOR A CARPET.

SPECIFICATION forming part of Design No. 19,496, dated December 17, 1889.

Application filed November 23, 1889. Serial No. 331,388. Term of patent 3½ years.

To all whom it may concern:

Be it known that I, EDWARD POOLE, a subject of the Queen of Great Britain, and a resident of Philadelphia, Pennsylvania, have invented a Design for Carpets, reference being had to the accompanying photographic illustration, in which—

A A are flowers bearing a general resemblance to the chrysanthemum.

10 B B are sprays of leaves.

C C are sprays of grasses.

D D are sprays of small flowers and leaves.

D' D' are large flower-shaped figures made up of leaves, resembling scroll-work.

F F are clusters of flowers, each having a 15 center with diverging leaves.

What I claim as new is—

The design for carpets, as shown.

In witness that the above is my invention I have hereunto set my hand.

EDWARD POOLE.
